UNITED STATES PATENT OFFICE.

JAMES E. GILLESPIE, OF BOSTON, MASSACHUSETTS.

IMPROVEMENT IN STEAM-TRAPS.

Specification forming part of Letters Patent No. 58,808, dated October 16, 1866.

To all whom it may concern:

Be it known that I, JAMES E. GILLESPIE, of Boston, in the county of Suffolk and State of Massachusetts, have invented a new and useful device for relieving steam-pipes of water that may accumulate in them by reason of condensation; and I do hereby declare that the following is a full, clear, and exact description thereof, reference being had to the accompanying drawing, and to the letters of reference marked thereon.

The nature of my invention consists in a small vessel attached beneath the steam-pipe in such manner that the water of condensed steam that may form in the pipe shall flow freely into it through a small pipe, and flow out at the bottom of the vessel freely, without allowing any steam to escape with it; all of which is accomplished automatically and without any outside appliances.

To enable others skilled in the art to make and use my invention, I will proceed to describe its construction and operation.

In the annexed drawing, *a* represent an ordinary steam-pipe. At the lowest point, where water would naturally accumulate, I attach a small pipe, of suitable material to resist any tendency to corrode, and also that will, when wound around like a spiral spring, have a considerable degree of elasticity. The number of turns given will depend upon the amount of elasticity desired. At the lower end of this hollow spring I attach a tank or vessel, *c*, capable of containing a sufficient quantity of water to stretch the coil *b* downward by its weight when partially filled. Inasmuch as the coil is really a spring, it is plain that the weight of water will stretch it just in proportion to the quantity in the vessel. At the bottom *d*, I make a valve of any convenient form, and extend a stem, *e*, down through the aperture in the bottom of the vessel *c*, and immediately beneath the end of the valve-stem I place a bar, post, or any other convenient device, so adjusted that when the vessel *c* shall be more or less supplied with water, (the amount depending upon the stiffness of the pipe *b*), and settle down by reason of the increased load hanging upon the coil, the stem of the valve shall be brought in contact with the post or bar and stopped in its downward motion, and thus lift the valve from its seat and allow the water to flow out around the stem until so much shall have passed out that the load is no longer able to depress the spring

sufficiently to open the valve, when it will close by the pressure exerted upon the top of it by the steam and weight of water, as well as by its own weight.

In practice I shall, when convenient, inclose the whole apparatus in a case or basket of wire or other suitable material, to the bottom of which a waste-pipe can be attached, to carry off the discharged water, and the case, being attached to the steam-pipe, will serve to protect the coil and tank from accident.

I do not wish to confine myself to the particular form or arrangement of the coil, as it is evident that sufficient motion and elasticity can be obtained from a pipe running nearly horizontal, if the vessel is attached at one end and allowed free action up and down. It is also plain that the same result can be obtained by using a flexible pipe and supporting the tank *c* upon auxiliary springs, or even by suspending it with a dead-weight for a balance; or many other modes of arranging the different parts could be suggested; but the principle remains the same, and the operation in all will be the same or equivalent. Thus the water that accumulates in the steam-pipe, or, indeed, in any other kind of a vessel where steam or other gas is contained for any purpose whatsoever, will flow into the tank *c* until its weight is sufficient to depress the tank enough to cause the valve to open slightly, and thus it will hang steadily, with the valve just sufficiently open to allow all the water to pass off continuously, always settling down just in exact proportion to the amount of water accumulated in the tank, and, by the fact of so settling down, opening the valve just enough to allow it to pass out as fast it flows in, while at the same time, if there is no water to be discharged, there is then nothing to stretch the coil, and therefore the valve *d* will remain tightly closed and prevent any waste of steam, the entire apparatus being automatic and reliable.

What I claim, and desire to secure by Letters Patent, is—

A steam-trap constructed and applied substantially as herein set forth.

JAMES E. GILLESPIE.
